UNITED STATES PATENT OFFICE.

JAMES H. BLESSING, OF ALBANY, NEW YORK.

SEPARATOR FOR REMOVING LUBRICANT FROM EXHAUST-STEAM.

SPECIFICATION forming part of Letters Patent No. 514,439, dated February 13, 1894.

Application filed May 26, 1893. Serial No. 475,542. (No model.)

To all whom it may concern:

Be it known that I, JAMES H. BLESSING, of the city and county of Albany, in the State of New York, have invented new and useful 5 Improvements in Separators for Removing Lubricant from Exhaust-Steam, of which the following is a specification.

My invention consists of a casing having nozzles at opposite ends for connecting the 10 apparatus in a line of exhaust-pipe; said casing being divided into several compartments, by means of transverse partitions provided with steam-openings ranging in line with, and having the same area as, the openings through 15 said nozzles; each of said compartments containing a series of pendent gutter-like plates which are spaced apart to leave open spaces between the edges of the adjacent plates of the same row, the open space of one row being arranged to come opposite to a plate of the succeeding row, whereby the exhaust steam will be forced to pass in a zig-zag direction through the apparatus; the hollow side of said plates being faced toward the incoming steam, and a retardation of the steam is 20 effected in each compartment whereby a more perfect separation of the lubricant from the water condensed from the steam will be obtained.

30 In the accompanying drawings, which are hereby referred to and form part of this specification, Figure 1 is a longitudinal section of my separator. Fig. 2 is a transverse section of the same, at the line X X on Fig. 3. Fig. 35 3 is a plan view of my separator without the bonnet for covering the same, the pendent gutter-like plates being shown in horizontal section; and Fig. 4 is a horizontal section of my separator at the line Y Y, the waste-water 40 valves and two of the oil-gages being shown in plan view.

As represented in the drawings, A designates the casing of my separator which is preferably made in the form of an oblong rectangular box that is open on its upper side, and is divided into a series of compartments by means of transverse partitions, B, each of which is provided with an opening, C, through 45 which the steam can pass from one compartment to the next one in succession. At one

end of said casing there is an inlet nozzle, D, through which the exhaust steam will enter the first compartment, and at the opposite end of said casing there is an outlet nozzle, E, through which the steam escapes from the 55 last compartment after the lubricant is separated from the steam; said nozzles and the openings C are preferably made to range on the same line and are practically of the same area. A bonnet, F, is fitted to form a steam-tight joint on the upper side of the casing A and forms a closure for the open top of the latter. Pendent from said bonnet is a series 60 of gutter-shaped plates, G, which effect a retardation of the steam through the apparatus, 65 and, by the impact of the steam against said plates, effects the separation of the steam and lubricant. The plates G are arranged in parallel lines crosswise of the casing A, in groups that correspond to the number of compartments in said casing, so that a group of the plates will be contained in each compartment. 70 The plates G have their concave faces turned toward the inlet nozzle D, and are spaced apart to leave an opening, H, between the 75 edges of the adjacent plates of the same row; the openings of one row being arranged to come opposite to a plate of the succeeding row, whereby the steam passing through a compartment will be obliged to pursue a zig-zag course. When the steam enters the first 80 compartment of the apparatus, the increased area of the chamber allows the steam to expand and effect a diminution of the initial pressure and velocity thereof, but with each successive impulse of the exhaust, the pressure will be restored to the initial point and the steam will pass through the successive 85 openings C with practically the same velocity with which it passed through the nozzle D, 90 and this action will recur as often as the steam passes from one compartment to another. As above stated, when the steam strikes the plates G the impact will cause a separation of the lubricant from the steam, 95 and, from the greater affinity of the lubricant for the metal, said lubricant will temporarily attach itself to the plate, from which it will trickle, and become deposited on the surface of the water, produced from the condensation 100

of the steam, which accumulates in the lower part of each compartment.

I designate the equalizing-passages which lead from the upper portion of each compartment to the lower part of the same; said passages are provided for the purpose of equalizing the pressure acting upon the liquids contained in the lower part of each compartment so that said liquids cannot be prematurely ejected therefrom; each of said passages is provided with an upper port, 1, and a lower port, 2, which communicate with the compartment to which the passage is appropriated; said passage being isolated from the interior of its compartment except through the medium of its ports. Each of the passages I has a waste-water pipe, J, leading from it, said pipes being arranged at a height corresponding to a level at which it is desirable to maintain the liquids in the apparatus, said pipes being provided for the purpose of draining the water from the corresponding compartments during the time the lubricant is accumulating therein, the level of the water above the port 2 preventing the lubricant from passing from the compartment into the passage I, and thence out of pipe J. Each of the waste-water pipes is provided with a valve, K, for the purpose of closing the communication through said pipe while the lubricant is being expelled from the corresponding compartment. Each compartment has a pipe, L, leading therefrom, said pipes being preferably arranged so that the lower side of the bore will be slightly lower than the corresponding part of the bore of the pipes J. The outer end of each of the pipes L is provided with an oil-gage, M, having transparent sides for the purpose of affording visible evidence of the level of the lubricant in the corresponding compartment, and each of said gages is provided with a cock, N, for the purpose of drawing the lubricant from the compartment to which the cock is appropriated.

My invention operates in the following manner: The casing A being secured in the line of the exhaust-pipe of a steam engine, so that the nozzle D will be toward the engine, the outer portion of said exhaust-pipe can be connected to a feed-water heater or arranged to discharge the exhaust steam into the atmosphere. The exhaust steam from the engine will enter the first compartment of the apparatus and therein become expanded as hereinbefore explained, it then enters the next compartment to undergo another expansion, and in like manner it will continue until the steam has entered every compartment and issues from the apparatus with substantially the same velocity with which it entered through the nozzle D. While passing through the several compartments, the steam, by its impact with the plates G, will be separated from the lubricant, the latter falling to the bottom of the compartment

wherein the separation has taken place, the quantity of lubricant collected in the successive compartments will become less, as the operation is continued, until all the lubricant has been eliminated from the steam. When a gage M, appropriated to any particular compartment, indicates that a sufficient quantity of lubricant has been collected in said compartment to warrant its discharge therefrom, the waste-water valve K, pertaining to said compartment, must be closed and the corresponding cock N opened; when this has been accomplished, the lubricant will run out of said cock, and will continue to do so until all of the lubricant is discharged from that compartment, which fact will be manifested by a profuse escape of steam from said cock N. While the valve K remains closed, to prevent the outflow of water, the continued condensation of the steam in the compartment will cause the water to rise therein and effect a corresponding elevation of the lubricant which is floating on the surface of the water, and thereby the discharge of the lubricant from the compartment will be facilitated. When all of the lubricant is discharged from a compartment, the cock N should be closed and the valve K opened, thereby restoring the parts to a condition to effect a repetition of the operation just described.

By reason of the water remaining in the lower part of each compartment—the level of said water never falling below the openings of the pipes J—a water seal will thereby be formed in each compartment to prevent the lubricant from passing into the passage I of the corresponding compartment.

What I claim as my invention, and desire to secure by Letters Patent, is—

1. A separator for eliminating lubricant from exhaust-steam, consisting of a casing provided with inlet- and outlet-openings for the steam, and a series of transverse partitions which divide said casing into a corresponding series of communicating compartments; each of said partitions being provided with a single opening which is practically of the same area and ranges in line with said inlet- and outlet-openings, and each compartment containing a group of retarding-plates that are pendent from the bonnet of said casing and are arranged as herein described; whereby the steam will be compelled to pass in a zigzag direction through each of said compartments, as and for the purpose herein specified.

2. A separator for eliminating lubricant from exhaust steam, consisting of a casing divided into a series of communicating compartments by means of transverse partitions provided with openings ranging in line with—and practically having the same area as—the inlet- and outlet-openings of said casing, each compartment being provided with a pressure-equalizing passage which forms an independ-

ent communication between the upper and lower part of the compartment, and each of said passages having a waste-water pipe which leads therefrom alone at a height corresponding to the level at which the water is to be maintained in the apparatus; whereby an independent water-seal will be formed in each

compartment to prevent the escape of lubricant through said waste-water pipe, substantially as herein specified.

JAMES H. BLESSING.
